UNITED STATES PATENT OFFICE.

CHARLES E. RICE, OF DELRAY, FLORIDA.

RAILROAD GATE.

Application filed November 18, 1925. Serial No. 69,419.

To all whom it may concern:

Be it known that I, CHARLES E. RICE, a citizen of the United States, resident of Delray, in the county of Palm Beach and State 5 of Florida, have made a certain new and useful Invention in Railroad Gates; and I declare the following to be a full, clear, and exact description of the same, such as will enable others skilled in the art to which it 10 appertains to make and use the invention, reference being had to the accompanying drawings, and to letters or figures of reference marked thereon, which form a part of this specification.

15 The invention has relation to means for operating railroad gates at crossings and other similar places, having for an object to provide improved means for automatically doing this work upon passage of the 20 car or train in either direction and for automatically returning the gate to first or inoperative position.

25 The invention consists in the novel construction and combination of parts, as hereinafter set forth.

In the accompanying drawings illustrating the invention, Figure 1 is a plan view of the invention somewhat diagrammatic showing the gates as set to operative position and 30 the car approaching a crossing; Figure 2 is a side view of the same; Figure 3 is a side view of the invention partly in section and parts broken away on a somewhat larger scale, parts being shown in adjusted positions in dotted lines, parts being in normal 35 position in full lines; Figure 4 is a detail plan view of the latch to hold the gate set to operative position; Figure 5 is a detail view of one of the drums showing the cables 40 and Figure 6 is a detail sectional view of the guideway wherein works the device actuated by the ramp upon the car or train.

45 In these drawings, the numeral 1 designates a railroad gate of any approved form, to the pivot 2 of which is fast a drum 3, whereon is wound in one direction a cable 4, one end of which is extended downwardly at 5 around guide pulley 6, and horizontally extended at 7 along one side of the railroad 50 track 8 a sufficient distance away from the crossing and having its termination attached to coiled spring 9, the other end of said spring being connected to slide 10 having an upward projecting lug 11, adapted for engagement with the ramp of a locomotive, or

other car, said slide working in guideway 12. The other end of said cable 4 is extended downwardly at 13 around guide pulley 14 and thence horizontally at 15 in a direction 60 opposite to that of the said end portion 7 of the cable, along the same side of the track as end portion 7 a sufficient distance and then around a guide pulley 16 and extended reversely at 17 and having its terminal connected to coiled spring 18, the other end of said spring being connected to a slide 19, working in guideway 20 and having an upward projecting lug 21 adapted for operation by the ramp 22 of a locomotive or car. 70

Upon operation of the slide 19 by ramp 22, the movement of said slide in its guideway will extend the spring 18 to exert tension upon the cable 15 and thereby rotate the drum 3 and set the gate from vertical 75 to horizontal position, where it is engaged and yieldably held by spring latch 23, the slide at the end of its guideway moving laterally due to a lateral offset 20' of the latter and thus escaping from the said ramp, 80 whereupon said slide will be reversely moved by its spring, to take up excess movement thereof in escaping said ramp as stated.

The locomotive or car having passed the 85 crossing it is desired to return the gate to vertical position and to this end ramp 22 of the locomotive engages the lug of the other slide 10, thereby extending the coiled spring 9 and exerting tension upon the said 90 end portion 7 of the cable to rotate said drum 3 and return the gate as stated with sufficient force to overcome the comparatively slight resistance of the spring latch 23, the lug of the slide escaping from the 95 ramp by lateral movement in a lateral extension 12' of said guideway in the same way as before stated, and the spring 9 returning the slide automatically to normal position, the tension upon the cable simultaneously returning the slide 19 to normal 100 position. It will be noted that the normal position of slide 19 is at one end of its guideway 20, and the normal position of the slide 10 is at the other end of its guideway 105 12, and that in the operation of the slide 19 to set the gate to operative or horizontal position, the said slide 10 is moved to the other end of its guideway 12, preliminary to operation to set the gate to inoperative 110 or vertical position. The coiled springs en-

able tension to be exerted upon the cable in such a yielding manner as not to impose too much shock or strain upon the parts.

- A duplicate set of devices is arranged 5 upon the other side of the track in reversed relation for the purpose of operating the gate upon that side of the track, (the same numerals being employed for designating the parts) by a train or car traveling in 10 the opposite direction, whereby the gate will be thrown by a train traveling in either direction, and in order that both gates shall be thrown to operative or inoperative position simultaneously, the two drums 3, which 15 are located diagonally opposite each other, are connected by a cable 25, passing around guide pulleys 26 and so wound and directed as to cause the one drum to be operated or rotated when the other is rotated. It will 20 be noted that the coiled springs also hold the cables taut at all times and yield in harmony.

I claim:—

1. Means for automatically operating railroad gates, including a drum upon the pivot 25 of the gate and having a cable wound thereon, a guideway spaced from said gate at one side thereof and having a slide working therein, said slide having a spring connection with one end portion of said cable 30 and being operable by a ramp upon the

car to tension said spring connection to thereafter set the gate to operative position, and a guideway spaced from said gate at the opposite side thereof and having a slide working therein, said slide having a spring 35 connection with the other end portion of said cable and being operable by said ramp of the car to tension said spring and thereafter set the gate to inoperative position.

2. Means for automatically operating two 40 laterally opposite railroad gates, including a drum upon the pivot of each gate and having a cable wound thereon, a guideway for each gate spaced therefrom at one side thereof and having a slide working therein, 45 said slide having a spring connection with one end portion of its related cable and being operable by a ramp upon the car to tension said spring connection to thereafter set both gates to operative position, and a 50 guideway for each gate at the opposite side thereof and having a slide working therein, said slide having a spring connection with the other end portion of the related cable and being operable by said ramp of the 55 car to tension said spring connection and thereafter set both gates to inoperative position.

In testimony whereof I affix my signature.

CHARLES E. RICE.
